UNITED STATES PATENT OFFICE

FRANZ HIRSCHSON, OF BERLIN, GERMANY

PHOTOMETER, PRINCIPALLY FOR PHOTOGRAPHIC AND PYROMETRIC PURPOSES

Application filed January 8, 1927, Serial No. 159,963, and in Germany January 14, 1926.

In photometers with an electric incandescent lamp producing the comparison-brightness, exact measurement of the intensity of current is necessary, if an absolutely constant intensity of current is not at disposal. 5 Devices are known, whereby this measurement is effected with one of the ordinary electric measuring-instruments. Devices are also known, whereby the intensity of current, prevailing during the moment of measuring, is not ascertained, but a standard intensity of current fixed, from which the comparison-brightness is obtained by a change of resistances. 10

15 The value of this change in resistance indicates under certain presumptions the brightness of the lamp.

This kind of measuring has the disadvantage, that an equally great change in resistance must render different results, if care is not taken to eliminate faults arising from the regulating-resistance for the required measurement and obtaining a standard intensity, which depends upon the prevailing battery-tension which may vary over different values. The object of the present invention is to provide an arrangement in which the value of the current flowing through the lamp during photometric measuring, can be exactly ascertained without the employment of a special measuring-instrument. 25

The advantage of direct measurement of the current resides in the elimination of the above described source of errors. My invention utilizes a fixed standard intensity of current which is indirectly used as basis for further measurements as will be more clearly described hereinafter. 35

In the system of my invention an independent resistance of high temperature-coefficient is connected with the circuit formed by the battery, regulating-resistance and photometric lamp as set forth in more detail in the following specification. 40

A separate incandescent lamp is particularly adapted to this purpose, which is however merely used as resistance and not as source of light and is therefore hereafter referred to as a "resistance-lamp." Heating of 45 the incandescent filament of this resistance-

lamp involves a considerable increase of its self-resistance, the value of which can serve as the criterion for the intensity of current and consequently also for the brightness of the photometric lamp in the same circuit. 55

Another arrangement is utilized, whereby this self-resistance of the resistance-lamp can be measured. This is done in a very simple manner by disconnecting the resistance-lamp from the circuit by means of a throw-over switch and replacing the same by a suitable adjustable resistance. 60

In case of consonance of this resistance with the resistance of the resistance-lamp, the ratio of current is not altered in the total circuit and it may be thereby observed, that the photometric lamp is glowing with unchangeable brightness, irrespective of whether the gauged resistance is connected with the circuit or the resistance-lamp. In executing a 70 measurement, the photometric lamp is first adjusted to the source of light to be measured and the regulating-resistance alternately connected with the circuit in a process of substituting, by actuating a switching system. If 75 this resistance does not correspond with the one of the lamp, this fact is observable by a fluctuation in the brightness of the photometric lamp and so, with great exactness, as this lamp has previously been adjusted to the 80 brightness to be measured, by altering the regulating-resistance, the photometric lamp is again brought to its former brightness and the resistance of the resistance-lamp can now be read from the position of the gauged regulating-resistance. In practice, the gauge-scale will be arranged in values of brightness of the source of light to be measured, but in using the instrument as an optical pyrometer, the instrument may be calibrated in values of temperature. 85

Figure 1 is a cross-sectional view taken through the photometer of my invention; Fig. 2 is a front view of the photometer with the casing partially broken away and illustrating the switching mechanism therein; Fig. 3 is a wiring diagram showing the arrangement of circuits for the photometer; and Fig. 4 is a modified wiring diagram of the circuits for the photometer. Fig. 5 shows 95 100

a part of the instrument in its application as pyrometer.

The photometric lamp 1 is observed through an ocular glass 2, in the field of view of which a matt disc 3 is visible. It is arranged in well known manner behind an open, inside blackened tube 4 and receives thus the average brightness of the picture-angle indicated by dotted lines, Fig. 1. The blackened pipe has the purpose, to permit only such rays to strike the matt disc, emanating from the points located inside the picture-angle of standard photographic objectives. The current, which may be taken from a pocket-lamp-battery, is controlled by the regulating-resistance 5, until the incandescent filament has obtained the brightness of the matt disc, or in other words the physical outline of the filament disappears. The judging this condition may be facilitated by utilizing a color-filter 11, and directing both sources of light upon the same color. If the switch button 6 is now pressed down, (Figs. 2 and 3), a transfer of electrical connections is effected and the resistance-lamp 7 is replaced by the regulating-resistance 8, the adjustment of which serves for reading the brightness of light as above described.

In using the instrument and optical pyrometer, Fig. 5, a collecting lens 3' is employed instead of the matt disc, whereby a sharp picture of the object to be measured is obtained in the plane of the incandescent filament. In this kind of employment of the instrument, the filament is not tuned on a uniformly light back-ground as in the case of the pyrometer, but tuning is done in such a manner, that the object to be measured appears sharply in the field of view. In the photometer for photographic purposes, it is not essential, to measure the lucidity of a certain, sharply limited part of a picture, but the average total lucidity which is important for the exposure has to be ascertained. A fundamental difference between photometer and pyrometer does not exist, as the pyrometer can, upon suitable gauging, immediately be used as photometer, if the lucidity of a uniform illuminated surface is to be measured, as for instance the lucidity of a work-table, upon which a sheet of white paper is placed.

Fig. 4 illustrates a modified circuit arrangement for the photometer of my invention. The resistance-lamp 7, and the substitution regulating-resistance 8 is in this case connected in parallel to the photometric lamp 1. The operation of the circuit of Fig. 4 is the same as in connection with Fig. 3. The shunt 9 of predetermined value as used in Fig. 3 may be omitted in the arrangement of Fig. 4.

As the exactness of the measurement depends upon the extent of the change in resistance of the resistance-lamp, the latter is

advantageously so selected, that its consumption of current is less than the one of the photometric lamp. In this case, slight changes in brightness will be perceptible in the resistance-lamp in form of correspondingly increased resistance-changes in the other lamp. In practice, an exact syntonizing of the conditions of current in both lamps can be obtained thereby, and the shunt 9 of predetermined value connected parallel to the photometric lamp whereby the consumption of current is increased in a manner exactly calculable. To the maximum brightness coming in question for the photometric lamp, full white heat will in this case correspond to the resistance-lamp. This shunt 9 to the photometric lamp is illustrated in Fig. 3.

Calibrations are provided on the exterior of the casing of the photometer adjacent each of the operating knobs 9, 10 which control the effective values of resistances 5 and 8 and direct readings are taken from the instrument by noting the calibrations for any selected setting.

While I have described my invention in certain of its preferred embodiments, I desire that it be understood that modifications may be made and no limitations upon my invention are intended other than are imposed by the scope of the appended claims.

I claim:

1. In a photometer a circuit containing a battery, a regulating-resistance, a photometric incandescent lamp connected in series with said battery and resistance, an independent resistance of high temperature coefficient, a regulating and gauged resistance, a switch connected in circuit with said lamp and resistances and adapted to cut out said resistance of high temperature coefficient from the circuit and to cut in said regulating and gauged resistance into the circuit for effecting photometric measurements.

2. In a photometer a circuit containing a battery, a regulating-resistance, a photometric incandescent lamp connected in series with said battery and resistance, a second incandescent lamp, a regulating and gauged resistance, a switch connected in circuit with said lamp and resistances and adapted to cut out said second incandescent lamp from the circuit and to cut in said regulating and gauged resistance into the circuit for effecting photometric measurements.

3. In a photometer a circuit containing a battery, a regulating-resistance, a photometric incandescent lamp connected in series with said battery and resistance, a second incandescent lamp, said second lamp having a smaller consumption of current than said photometric lamp, a regulating and gauged resistance, a switch connected in circuit with said lamp and resistances and adapted to cut out said second incandescent lamp from

the circuit and to cut in said regulating and gauged resistance into the circuit for effecting photometric measurements.

4. In a photometer a circuit containing a battery, a regulating-resistance, a photometric incandescent lamp connected in series with said battery and resistance, an independent resistance of high temperature coefficient, a regulating and gauged resistance, a switch connected in circuit with said lamp and resistances and adapted to cut out said resistance of high temperature coefficient from the circuit and to cut in said regulating and gauged resistance into the circuit, and a shunt resistance connected in parallel to said photometric lamp in said series circuit.

5. In a photometer a circuit containing a battery, a regulating-resistance, a photometric incandescent lamp connected in series with said battery and resistance, a second incandescent lamp, a regulating and gauged resistance, a switch connected in circuit with said lamp and resistances adapted to cut out said second incandescent lamp from the circuit and to cut in said regulating and gauged resistance into the circuit, and a syntonized shunt resistance connected in parallel to said photometric lamp in said series circuit.

6. In a photometer a circuit containing a battery, a regulating-resistance, a photometric incandescent lamp normally connected in a series circuit with said battery, a second incandescent lamp, said second lamp having a smaller consumption of current than said photometric lamp, an independent regulating and gauged resistance, a switch connected in circuit with said second incandescent lamp and independent resistance and adapted to cut out said second incandescent lamp from the circuit and to cut in said regulating and gauged resistance into the circuit, and a shunt resistance disposed in parallel to said photometric lamp in said series circuit.

In testimony whereof I have affixed my signature.

FRANZ HIRSCHSON.
